OR D 13,728

DESIGN FOR A LAUNDRY-STOVE.

Design No. 13,728, dated March 13, 1883.

UNITED STATES PATENT OFFICE.

JOHN RINGEN, OF ST. LOUIS, MISSOURI.

DESIGN FOR A LAUNDRY-STOVE.

SPECIFICATION forming part of Design No. 13,728, dated March 13, 1883.

Application filed December 11, 1882. Term of patent 14 years.

To all whom it may concern:

Be it known that I, JOHN RINGEN, a citizen of the United States, residing in the city of St. Louis, Missouri, have invented and produced a new and original Design for Laundry Stoves, of which the following is a specification, reference being had to the accompanying photograph, forming part thereof, in which the stove in question is shown in perspective, the stove-doors being opened.

The present laundry-stove is distinguished by the appearance of the fuel-chamber and the stove-top.

The base A of the stove is of the usual form. The fuel-chamber B, in place of the customary shape, has the iron-recesses b b in the lower part, b', of the chamber, as shown. The peculiarity of the stove-top C is the extension c, which projects from the center of the main portion c' of the top rearwardly. The main portion c' of the top, or that portion immediately over the fuel-chamber, is of the

usual oval shape. The extension c is considerably narrower in top view than the portion c', and, as seen in side elevation, is quite shallow compared with the total depth of the body of the stove.

I claim—

1. The design for a laundry-stove herein shown and described, the same consisting, in combination, of the fuel-chamber B, having the recesses b b, arranged as described, and the top C, having the extension c.

2. The design for a laundry-stove herein shown and described, the same consisting of the fuel-chamber B, having the recesses b b arranged at the lower part of the chamber.

3. The design for a laundry-stove herein shown and described, the same consisting of the top C, having the extension c.

JOHN RINGEN.
